REGENERATED CELLULOSE TUBING AND
METHOD FOR MAKING THE SAME

Peter D. Massoline, Jersey City, N. J.

Application August 9, 1941, Serial No. 406,207

3 Claims. (CL. 93—94)

This invention relates to new and useful improvements in decorative regenerated cellulose tubing, as for example "Cellophane" tubing, and an improved method for making the same.

It is to be understood whenever, in describing and claiming the present invention, the word "tubing" is used herein it is not to be read in the commonly accepted sense thereof but is meant to indicate the product resulting from twisting or curling each of the side edges of a length of regenerated cellulose tape until the rolled edges meet.

"Cellophane" tubing is employed in many and varied decorative schemes and in the manufacture of ornamental novelties such for example as Christmas wreaths, miniature Christmas trees, as a background for food displays, as a packing medium in gift boxes and the like. Heretofore, plain smooth surface unscored "Cellophane" tubing has been employed for such purposes.

The principal object of the present invention is to produce "Cellophane" tubing having an irregularly crimped surface which is highly ornamental and decorative and whose light reflecting properties are superior to that of plain smooth surface tubing. To this end a method is provided which in forming the tubing produces permanent, irregular, obliquely disposed crimping or scoring along the length thereof, resulting in the attainment of a tubing with a novel and striking surface having unique light reflecting properties similar to the light reflection given by the facets of a diamond.

In the annexed drawing of a preferred embodiment of the invention:

Fig. 1 is a perspective view of a complete apparatus employed in making the improved decorative regenerated cellulose tubing of the present invention;

Fig. 2 is a sectional view showing in detail the forming and crimping device of Fig. 1;

Fig. 3 is an enlarged view of the small end of the forming and crimping device of Fig. 2, showing the front end of its crimping flange;

Figs. 4 and 5 are perspective views of two forms which a length of the novel, crease-marked tubing may take; and

Fig. 6 illustrates the appearance of a section of the finished tubing of Fig. 4 unrolled and returned to substantially its initial ribbon form to show the irregular scoring or crimping.

In general, the apparatus shown in Fig. 1 is a modified conventional tubing machine such as is employed in the manufacture of cloth tubing for artificial flower stems and the like and

it comprises a plurality of "Cellophane" ribbon feeder reels 2 rotatably mounted in spaced relationship upon a common shaft 6, a plurality of guide pins 3, a heated die 4 having a plurality of equi-distant, transverse, funnel-like, openings 11 therethrough, in each of which is located one of the conical forming and crimping devices 8, a source of heat for die 4 such as a gas flame 13 and a drum 5 to receive the finished tubing, all supported on a base 1 and having appropriate drum driving mechanism, not shown, such as an electric motor, adapted to slowly rotate the winding drum. If desired, the feeder reels 2 may, of course, be supported on a base separate from that supporting the rest of the apparatus.

In the method of the present invention, the free end 7 of each of the "Cellophane" ribbon reels 2 is drawn between a pair of guide pins 3 into one of novel, heated, conical-shaped forming and crimping devices 8 shown in detail in Figs. 2 and 3 and which hereinafter will be referred to as a "crimper."

The large end of crimper 8 is provided with a hooked portion 9 adapted to slide over and engage a flange 10 adjacent die 4 when the apex end of the crimper has been properly inserted into the conical end of one of the funnel-shaped openings 11 of heated die 4.

The novel crimping or scoring of the tubing 30 is accomplished by having the vertical inner flange 12 of crimper 8 extended to the edge of, and almost completely divide in half, the inside of the small or apex end of the crimper, leaving just sufficient space between its lower edge and the lower inner surface of the crimper to snugly receive therebetween the particular thickness of "Cellophane" tape or ribbon which is being fabricated into tubing.

As will be evident from examination of Figs. 2 and 3, the horizontal distance between either side of flange 12 and the adjacent inner surface of crimper 8 gradually decreases as the small or apex end of the crimper is approached.

Now, as the flat "Cellophane" ribbon 7 is drawn through heated crimper 8 by the finished tubing to which it is attached (and which itself is being slowly wound on the rotating drum 5) the gradually decreasing diameter of the inside of the crimper causes each of the side edges of the ribbon to continuously curl or twist upwardly against the inside of the crimper wall and then downwardly against the side of the flange 12 (as shown in Fig. 3) until the full width of the initially flat ribbon or tape has been accommodated in the 55 confined spaces on either side of the flange 12 by

the twisting or curling action. As a result, a more or less tubular form is acquired by the tape.

As the tape is drawn past that portion of heated flange 12 which is adjacent the small or apex end of crimper 8, the friction therebetween, while not great enough to cut the tape or ribbon or to cause it to break from the finished tubing being wound on the drum 5, is sufficient to cause a surface strain along the length of the ribbon at the line of contact with heated flange 12 resulting in the formation of irregular crease markings or crimping 14 extending diagonally out from and on either side of said line of contact. These irregular striations or crimps 14 are shown in detail in Figs. 4, 5 and 6.

After the tubing has emerged from the small end of crimper 8, it is pulled through the smaller diameter end 15 of heated die 4 where it is further decreased in diameter and where the action of the heat eliminates any tendency which the tubing might have to unroll and spring back to its initial ribbon form. Subsequent exposure to the air as it emerges from heated die 4 permanently sets or fixes the form and surface markings which the tubing has acquired in passing 25 through crimpers 8 and die 11.

While this application discloses a preferred embodiment of the invention, it should be understood that it is capable of modifications, and that such modifications may be employed without departing from the spirit and scope of the invention as expressed in the following claims.

I claim:

1. Regenerated cellulose tubing having a permanently diagonally crimped surface.
2. Decorative tubing comprising regenerated cellulose tape having its edges curled until the rolled edges meet and having its surface permanently, irregularly diagonally crimped.
3. The method of manufacturing decorative crimped tubing from a length of regenerative cellulose tape which comprises, simultaneously curling in the presence of heat, each of the edges of said tape until said curled edges meet while producing a continuous lengthwise strain along and within the central area of said tape of such a nature that the surface of said tape acquires permanent irregular and oppositely disposed diagonal crimps, and then permitting said tubing to cool.

PETER D. MASSOLINE.
